UNITED STATES PATENT OFFICE.

WILLIAM LANGRILL, OF BAY CITY, MICHIGAN.

AUXILIARY RESETTING MECHANISM.

No. 856,267.

Specification of Letters Patent.

Patented June 11, 1907.

Application filed June 6, 1906. Serial No. 320,417.

To all whom it may concern.

Be it known that I, WILLIAM LANGRILL, a citizen of the United States, residing at Bay City, in the county of Bay and State of Michigan, have invented certain new and useful Improvements in Auxiliary Resetting Mechanisms; and I do hereby declare the following to be a full, clear, and exact description of the invention, such as will enable others skilled in the art to which it appertains to make and use the same.

This invention relates to voting machines and is more particularly directed to auxiliary resetting mechanisms for voting machines.

It quite frequently happens that a careless or ignorant voter will actuate a key indicating a candidate for whom he does not wish to vote and in such case he desires to make a new selection, but under certain former constructions, he could not make a new selection as a key once depressed had to be registered, no provision being made for rectifying mistakes. Subsequently, voting machines were constructed whereby mistakes of this nature could be recalled, by means of a complicated mechanism which not only consumed considerable time, but also was liable to get out of order.

My invention has for one object to expeditiously and efficiently correct any mistake made by the voter which he desires to recall.

As herein illustrated, the present embodiment of my invention is particularly designed to be used in conjunction with those machines wherein the selective mechanism not only operates suitable registering mechanism, but also operates mechanism for preventing the selection of two or more candidates for the same office.

To this end my invention has a further object in that it is adapted not only to reset the registering mechanism, but also the mechanism for preventing the selection of two or more candidates for the same office.

In carrying out these and other objects, therefore, the invention consists in certain novel features and combinations of parts together with their equivalents such as will be more fully described hereinafter and particularly pointed out in the claims.

In the accompanying drawings, illustrating a single embodiment of which my invention is susceptible, Figure 1 is a view of a portion of a machine equipped with this device, parts being broken away to better disclose the invention. Fig. 2 is a horizontal sectional

view through the machine, showing this auxiliary resetting means and its coöperating parts, Fig. 3 is a detail view of a portion of the machine shown in vertical section and Fig. 4 is a detail view, partly broken away, of the trips and their resetting means.

A indicates any suitable voting machine, preferably comprising a casing for supporting the various operative mechanisms, among which are the depressible keys (1) (1), the inner ends of which are pointed as shown at (2) and are adapted to lie opposite the slotted guides (3) (3), between which are received a series of sections (4), (4^a), (4^b), the sections being reduced or undercut at their adjacent ends as shown at (5) such reduced ends normally lying in alinement with the slots (6) formed transversely through the guides. The sections are slidably received between the guides and the meeting undercut ends form a small opening in alinement with the slots (6) in the guides when the machine is ready for operation. The keys (1) (1) are arranged in horizontal rows, each row indicating the various candidates for a single office, so that the depression of one key in a row will cause the pointed end of the depressed key to pass transversely through the slots in the guides and between the undercut ends of the sections, spreading the two sections apart, the movement of the sections engaged by the key being communicated to the remaining sections on each side thereof to the end that the undercut meeting ends of all such sections are moved out of alinement with the pointed ends of those keys in the same row which are not depressed. An attempt to depress any of the remaining keys therefore will be frustrated since the point of such key will engage a section instead of passing between the reduced ends of adjacent sections, thus preventing the voter from selecting two candidates for the same office.

The protruding pointed ends of the keys depressed are adapted to engage trips (7) slidably mounted in undercut ways (7^a) on the rear faces of the vertical slats forming a portion of a vertically movable sash (8), such trips normally projecting laterally beyond one edge of the slats of the sash and lying in the path of movement of the pointed ends of the keys. On the opposite sides of the slats are located registers (7^b), the protruding end of the key adapted to crowd the trip transversely of the slat and into alinement.

ment with the register. A vertical movement of the sash will then bring the trip into engagement with the register to operate the latter, a suitable wiper (9) being located 5 above the register to reset the trip during the further movement of the sash. The registers and the wipers are stationary on the strips (7^x) constituting a portion of the frame of the machine, and in front of which the sash 10 reciprocates.

The sections (4^a) and (4^b) are permitted a slight play at opposite ends of the series to allow them to move in the guides and the mechanism for registering the vote may operate simultaneously with a resetting mechanism (not shown) so that the protruding ends of the keys will not lie in the paths of the trips when the latter are returned to normal position.

As one means for permitting the voter to reset the machine without having his selection registered, as for instance when the voter has inadvertently or accidentally pushed the wrong key, I may provide the following mechanism. Levers (13) are pivotally secured intermediate their ends to a suitable support, one end of each lever projecting out from the front face of the machine in position to be swung laterally by the voter, the opposite end of the lever being received in a bail or other connection (14), carried by a horizontal rod (15), shouldered as at (16) to limit its movement in one direction, the rod extending the entire length of the casing behind the movable sash, the ends of the rods being loosely received and supported for convenience in bearings in the casing. This rod is provided with a series of projecting pins (17) (17) the free ends of which normally lie adjacent the sliding trips (7) and beneath the respective registers. Furthermore, the levers themselves pass through apertures formed in the guides (9) and through the end locking sections (4^a) (4^a), the sections (4^b) (4^b) at the opposite end being equipped with projecting lugs (10) (10) adapted to lie in the path of side levers (11) (11) on the casing, such levers being pivoted intermediate their ends and being actuated by the engagement of a finger (12) on the sliding rod (15) which is adapted to engage the lower ends of the intermediate levers (11) (11). Thus a movement of lever (20) in one direction will operate to move the sections (4), (4^a) and (4^b) together so that they reoccupy their normal positions and also resets the trip (7) which may have been crowded over after the accidentally depressed keys have been returned to their normal positions.

The operation of this part of my invention is as follows—The voter having depressed the wrong key and desiring to reset the machine without having his inadvertent vote registered and also to enable him to select his real choice, will grasp the depressed head of the key

and pull it outward. The depression of the key, however, has shifted the sections so that he cannot vote for any other candidate for the same office and it has also crowded the trip (7) over so that if the sash (8) is raised his 70 vote will be registered for the candidate corresponding to the key inadvertently depressed. He will, therefore, grasp the protruding end of the requisite lever (13) and move it laterally. The levers (13) are permitted a limited movement only so that the displaced sections will be moved back to normal position, past which the levers are unable to move them. Hence, when the lever is oscillated, the sections are brought 80 back to their former positions, the recessed ends of the sections lying in alinement with the slots (6). Furthermore, the oscillation of the lever has caused its rear end lying in the bail (14) to slide the rod (15) laterally to 85 effect the resetting of the remaining sections and also bringing a pin (17) against the projecting trip (7) and forcing the latter back to original position, whereupon the voter can press the desired key, the resetting of the 90 sections and trip being simultaneous.

When the voter has at last indicated his selection or choice of candidates, he leaves the booth and in order so to do, the handle (20) is released from the locking hook (21) 95 and pushed toward the left (in the drawing) thereby swinging open the gate (22), the outward movement of which, by means of the connecting limbs (23) (23) causes the resetting frame (24) to replace the depressed keys 100 (1), such frame moving in oblique direction toward the key face (25) of the machine. The resetting frame carries a stud (26) connected by a link (27) with a forwardly projecting arm 28 carried by the shaft (29), the 105 ends of which are journaled, as at (30), to a stationary portion of the machine. The shaft is further provided with the rigid projecting bars (31), to the free ends of which are pivotally secured the links (32) in turn 110 pivotally fastened to the vertically sliding sash (8). Thus as the resetting frame (24) moves, the link connection between it and the shaft (29) will tend to rotate the latter, which by its connection will raise the sash (8) 115 guided in any suitable manner, as by the pins (33). The return movement of the resetting frame will, of course, lower the sash. As the sash ascends, the reduced ends of the trips, which have been crowded past the 120 edges of the slots of the frame (8) by the depression of the keys, will first engage the registers (7^b) to operate the latter and as the sash continues to ascend, such reduced ends will be brought into contact with the stationary wipers (9) which will force the trips back to normal position, after which the descent of the sash may be accomplished. These constructions, however, are more fully 125 shown and described in my copending appli- 130

cations filed on the same date herewith, Serial Nos. 320,418 and 320,419, to which the reference is made for a further understanding of the invention.

- 5 The resetting frame carries a series of parallel bars (34), one of which is shown in Fig. 2, which are adapted to engage the pins (35) of the depressed keys to move the keys back to their extended or normal positions.
- 10 From the foregoing it will be seen that I have devised a most simple, yet efficient means for resetting the mechanism accidentally operated as well as one which will not readily get out of order. It will be understood too that the auxiliary resetting mechanism is entirely separate and distinct from the mechanism for registering the vote and for resetting the mechanism after the vote has been registered. Furthermore, it is obvious
- 15 that many changes and alterations might be made in the form and arrangement of the several parts described without departing from the spirit and scope of my invention and hence I do not wish to limit myself to the exact construction herein set forth.

Having fully described my invention what I claim as new, is—

1. The combination in a voting machine, with a horizontal row of depressible keys, of a 30 single series of locking sections, the series adapted to be actuated by the depression of any one of the keys to prevent the depression of any of the other keys in the same row, a stationary registering mechanism, a movable 35 sash, trips movably mounted on the sash and normally lying in the paths of movement of the respective keys, the depression of one key adapted to throw its trip into alinement with the registering mechanism, means for reciprocating the sash, to cause the trip to engage the registering mechanism, a resetting wing, into engagement with which the trip is brought subsequent to its engagement with the registering mechanism and an auxiliary 40 resetting device for resetting the actuated trip and the locking sections prior to the movement of the sash.

2. A voting machine comprising depressible selective mechanism, registers stationary mounted on the machine, movable trips normally lying in the paths of movement of and actuated by the selective mechanism to assume positions in alinement with the registers, a pivotally supported lever, a slidably 55 supported rod engaged by the lever and projections carried by the rod and adapted to engage and reset the trips subsequent to the return of a depressed member of the selective mechanism.

- 60 3. In a voting machine, the combination with a row of selective members, of a series of locking sections actuated by the operation of any one selective member in the row, stationary registering mechanisms, a member independent of the selective members and mov-

able past the registering mechanisms, trips movably mounted on the member, the trips normally lying in the paths of movement of the respective selective members and adapted to be moved thereby into alinement with 70 their corresponding registering mechanism, a main resetting mechanism adapted to replace the actuated selective member and reciprocate the movable trip-carrying member to register the vote and reset the trips and locking sections, and an auxiliary resetting mechanism operable by the voter prior to the actuation of the main resetting mechanism, for replacing the locking sections and trips in their normal positions subsequently to the 80 return of an accidentally operated selective member.

4. A voting machine comprising a series of individual selective members arranged in rows, stationary registering members, means 85 normally lying in the paths of movement of the individual selective members and moved thereby into alinement with the registering members, a movable element supporting the first named means and actuated past the registering devices, for registering the vote, locking members interposed between the individual selective members and the first named means, the actuation of one selective member in a row adapted to actuate the locking members to prevent the actuation of additional selective members in the same row, resetting mechanism for actuating the movable member to register the vote, replace the first named means and the selective members and 90 auxiliary resetting mechanism adapted to replace the first named means and the locking members subsequent to the return of an actuated selective member to normal position 95 and prior to the actuation of the resetting 100 mechanism.

5. The combination in a voting machine comprising a series of keys, a slotted guide, any one of the keys adapted to pass through the slots in the guide, a series of sections in 110 the guide, the adjacent ends of the sections being reduced and normally registering with the slots, the entrance of a key into a slot adapted to crowd the sections apart to close the remaining slots of an auxiliary means for 115 resetting the sections, said means comprising a pivotally supported lever connected with one end section, a slidable rod actuated by the lever, a finger on the rod, a lever pivotally secured intermediate its ends to the casting, one end of the lever lying in the path of movement of the finger, a pin carried by the opposite end section, the free end of the last named lever adapted to engage the pin on the end section.

6. The combination in a voting machine comprising a series of selective keys, a slotted guide, the keys receivable in the slots, and a series of sections slidably received in the guide, the sections adapted to be crowded- 125 130

ed apart when any one of the keys passes into a slot in the guide, of a lever connected to one end section, a rod actuated by the lever, a suitably supported side-lever adapted 5 to actuate the opposite end section and a finger on the rod for operating the side lever.

7. A voting machine comprising a row of selective members, a row of stationary registers, a series of locking sections actuated 10 by the operation of any selective member to prevent the actuation of the remaining selective members in the row, a trip-carrying member movable independently of the selective members, a series of trips movably sup- 15 ported on the trip-carrying member, and normally lying in the paths of movement of the respective selective members, the trips adapted to be crowded into alinement with their respective registers by the operation of 20 their respective selective members, resetting mechanism for registering the vote, and resetting the trips, selective members and locking sections and auxiliary resetting mechanism operable by the voter prior to the actuation 25 of the main resetting mechanism, for replacing the locking sections and trips subsequently to the return of an accidentally actuated selective member.

8. The combination with a voting machine 30 comprising a series of keys, a slotted guide, any one of the keys adapted to pass through the slots, in the guide, and a series of sections in the guide, the adjacent ends of the sections being reduced and normally registering with 35 the slots, the entrance of a key into a slot adapted to crowd the sections apart to close the remaining slots of auxiliary means for resetting the sections, said means comprising a pivotally supported lever connected 40 with one end section, a slidable rod actuated by the lever, and means actuated by the rod for operating the opposite end section whereby the sections are moved toward each other.

9. The combination with a voting machine 45 comprising a row of keys, and a series of sections spread apart by the actuation of a single key, of a trip also adapted to be set by the actuation of a key, a stationarily supported lever pivoted intermediate its ends, the lever engaging one end section, a slidably supported rod actuated by the lever, and a pin on the rod adapted to engage and reset the trip to prevent registering the vote.

10. The combination with a voting ma- 50 chine comprising a row of keys and a series of sections spread apart by the actuation of a single key, of a suitably supported lever pivoted intermediate its ends, one end of the

lever passing through one end section of the series, a slidably supported rod actuated by 60 the lever, a finger carried by the rod, a side lever actuated by the finger, and a pin on the opposite end section engaged by the side lever to move both end sections toward each other simultaneously upon the withdrawal 65 of an accidentally actuated key.

11. The combination with a voting machine comprising a row of keys and a series of sections, the ends of which normally lie adjacent each other, the actuation of a single 70 key adapted to spread the adjacent sections engaged by the key, of an auxiliary resetting mechanism comprising a slidable rod, a lever engaging one end section of the series and the rod and means connecting one end of the rod 75 and the opposite end section to permit a movement of the lever to return the series of sections to normal position subsequent to the withdrawal of the actuated key.

12. In a voting machine, the combination 80 with a row of keys and a series of stationary registers, of a movable trip carrier independent of the keys, trips movably mounted on the carrier and normally lying in the paths of movement of the keys, the trips adapted to 85 be moved into alinement with their respective registers by the operation of the keys, a main resetting mechanism for resetting the keys and for moving the carrier to register the vote and to reset the trips, and an auxiliary resetting means operable by the voter 90 prior to the actuation of the main resetting mechanism, for replacing the trips subsequently to the return of an accidentally actuated key.

13. The combination in a voting machine with a row of keys, and a series of registers, of a movable member, means for actuating the movable member relative to the registers, trips carried by the movable member and normally lying in the paths of movement of the keys, whereby the trips are moved into alinement with the registers, and an auxiliary resetting means for the trips, such means comprising a slidable rod, means for enabling the voter to actuate the rod subsequent to the return of a key to normal position and pins on the rod for returning the trip to normal position.

In testimony whereof, I affix my signature 110 in presence of two witnesses.

WILLIAM LANGRILL.
